DESIGN.

E. E. LINDSEY.

ELECTRICAL CABINET OVEN.

APPLICATION FILED JUNE 9, 1919.

54,272.

Patented Dec. 9, 1919.

INVENTOR

Ernest E. Lindsey,

UNITED STATES PATENT OFFICE.

ERNEST E. LINDSEY, OF OROVILLE, CALIFORNIA, ASSIGNOR TO BAKE-RITE OVEN MANUFACTURING COMPANY, OF SAN FRANCISCO, CALIFORNIA, A CORPORATION OF NEVADA.

DESIGN FOR AN ELECTRICAL CABINET-OVEN.

54,272.

Specification for Design.

Patented Dec. 9, 1919.

Application filed June 9, 1919. Serial No. 302,995. Term of patent 7 years.

To all whom it may concern:

Be it known that I, ERNEST E. LINDSEY, a citizen of the United States, residing at Oroville, in the county of Butte and State of California, and having as my post-office address 603 Hearst Building, San Francisco, California, have invented a new, original, and ornamental Design for Electrical Cabinet-Ovens, of which the following is a speci-

fication, reference being had to the accompanying drawing, forming part thereof.

The figure is a perspective view of an electrical cabinet oven, showing my new design.

I claim:

The ornamental design for an electrical cabinet oven, as shown.

ERNEST E. LINDSEY.
